CLAIM

(21) Appl. No.: **29/136,183**

The ornamental design for a flexible Christmas tree and
indoor plant watering funnel, as shown and described.

(22) Filed: **Jan. 25, 2001**

DESCRIPTION

(51) LOC (7) Cl. **08-01**

FIG. 1 is a perspective view of the invention.

(52) U.S. Cl. **D8/1**

FIG. 2 is a front elevational view of the invention.

(58) Field of Search D8/1, 2; 47/48.5,

47/40.5; D23/200; D7/700; D11/125

FIG. 3 is a top view of the invention.

(56) **References Cited**

FIG. 4 is a bottom view of the invention.

U.S. PATENT DOCUMENTS

FIG. 5 is an elevational view of the flexible neck extended.

D353,186 S * 12/1994 Browning D23/213
5,410,839 A 5/1995 Granger 47/40.5
